ADJUSTABLE ARM SUPPORT

Abraham Rosenberg, Brooklyn, N. Y.

Application October 11, 1938, Serial No. 234,372

1 Claim. (Cl. 248—118)

My invention relates to an adjustable arm support for use in religious or quasi-religious ceremonies and more particularly for use in certain ceremonies of fraternal rituals.

5 In certain fraternal rituals it is ordained that an applicant taking his oath, on bended knee and raised arm, is to remain in this extremely fatiguing and even painful position for a considerable length of time.

10 With the foregoing in mind it is an object of my invention to provide an arm support which can be used in executing the ceremony in question and which renders it possible to retain a position, in which one knee is bent and one arm

15 is raised for any length of time without causing any fatigue. Another object of my invention is to provide a support which can be easily and readily adjusted to accommodate different persons.

20 I accomplish these and other objects by the arrangement and combination of elements set forth in the following description, claimed in the appended claim, and illustratively exemplified in the accompanying drawing in which:

25 Fig. 1 is a perspective view of an arm support according to my invention and

Figs. 2 to 4 are side elevational views of the three telescopic elements forming the support, respectively.

30 In the drawing 11, 12 and 13 denote three longitudinal elements. Element 12 is hollow and open at one end 14 thereof and this element has an inner diameter to slide over the end 15 of element 11. The open end 16 of element 13

slides in a similar manner over the closed end 17 of element 12. Each of the two outermost elements 11 and 13 has secured to its free end an outwardly open bow-shaped member 18, 19. On the elements 12 and 13 there are mounted adjacent the ends 14 and 16 thereof blade springs 20, 21 projecting beyond said ends. The projecting ends of the springs carry inwardly projecting plugs 22, 23, each adapted to engage at choice any one of a longitudinal series of holes 24, 10 provided in each of the elements 11 and 12. Thus, the length of the support and the distance between the two bow-shaped members 18—19 can be easily adjusted to any desired extent.

15 In use, the support is initially adjusted to the desired length. Then, when the applicant has taken his proper position, the bow-shaped members are placed upon the knee and under the raised arm to support the latter.

I claim:

20 An adjustable arm support, comprising a plurality of longitudinal elements telescopically mounted the one within the other, releasable means to fix said elements in any one of several relative adjusted positions with respect to one another, and two bow-shaped members opening 25 in opposite directions and having their bight portions secured to the free ends of the outermost telescoping elements, each of said bow-shaped members being equally adapted to rest on the upper leg of the user and to serve as support for his upper arm.

ABRAHAM ROSENBERG.
